(57) **CLAIM**

The ornamental design for a cannula protector with scleral markers as shown and described.

DESCRIPTION

FIG. 1 is an isometric view of the cannula protector with scleral markers of the present invention.

FIG. 2 is a front view of the cannula protector with scleral markers of the present invention.

FIG. 3 is a rear view of the cannula protector with scleral markers of the present invention.

FIG. 4 is a top view of the cannula protector with scleral markers of the present invention.

FIG. 5 is a bottom view of the cannula protector with scleral markers of the present invention.

FIG. 6 is a first side view of the cannula protector with scleral markers of the present invention; and,

FIG. 7 is a second, opposing (as to FIG. 6), side view of the cannula protector with scleral markers of the present invention.

The broken lines in the drawings indicate portions of the cannula protector with scleral markers that form no part of the claimed design.

1 Claim, 4 Drawing Sheets
